UNITED STATES PATENT OFFICE.

CLIFTON N. KEITH, OF SPRINGFIELD, OHIO.

DESIGN FOR A FINGER RING.

Application filed August 3, 1923. Serial No. 6,931. Term of patent 3½ years.

To all whom it may concern:

Be it known that I, CLIFTON N. KEITH, a citizen of the United States, residing at Springfield, in the county of Clark and State of Ohio, have invented a new, original, and ornamental Design for a Finger Ring, of which the following is a specification, reference being had to the accompanying drawing, forming part thereof.

Figure 1 of the drawing is an extended plan view of a finger ring showing my new design. Figure 2 is a side elevation of the finger ring.

I claim:

The ornamental design for a finger ring as shown.

In testimony whereof, I have hereunto set my hand this 25th day of July A. D. 1923.

CLIFTON N. KEITH.
